UNITED STATES PATENT OFFICE.

PETER SCHNURR, OF CHICAGO, ILLINOIS.

LATCHING MEANS FOR WINDOW SCREENS.

Application filed June 29, 1923. Serial No. 648,588.

This invention relates to window screens, and an object of the invention is to provide a rolling screen which may be adjusted as desired, and is movable independently of movement of the window sash, being carried by a spring roller detachably supported at the top of the window frame either inside or outside of the window as desired.

Another object of this invention is to provide a rolling window screen structure which includes channel members in which the edges of the screen engage, and to provide guides in the channel members over which reinforcing plates carried by the edges of the screen are movable to provide smooth and unimpeded movement of the screen during adjustment, and also to prevent buckling or crimping of the edges and adjacent portions of the screen.

A further object of the invention is to provide a novel form of latch mechanism for holding the screen in adjusted position.

Other objects of the invention will appear in the following detailed description taken in connection with the accompanying drawings wherein:

Fig. 1 is a front elevation of the screen.

Fig. 2 is a vertical section taken on the line 2—2 of Fig. 1.

Fig. 3 is a perspective view of an attaching bracket used in connection with the screen.

Fig. 4 is a perspective view of another attaching bracket used in connection with the screen.

Fig. 5 is an enlarged detail elevation of a part of the screen lock or latch structure.

Fig. 6 is an enlarged detail section on the line 6—6 of Fig. 1.

Fig. 7 is a perspective view of one of the guides of the screen structure.

Fig. 8 is a detail perspective view of one of the edges of the screen.

Fig. 9 is a section on the line 9—9 of Fig. 5.

Referring more particularly to the drawings, the improved rolling window screen comprises, preferably, a spring roller 1 of any approved construction which has a wire screen 2 attached thereto in the usual manner. Brackets 3 and 4 are provided for attachment to a window frame A for detachably supporting the roller 1 and these brackets are provided respectively with an open socket 5 opening out through its upper side and with a cylindrical socket 6. The brack-

ets 3 and 4 may have laterally turned attaching portions 7 formed thereon, as shown in dotted lines in Figs. 3 and 4 of the drawings or they may be straight as shown in solid lines in said figures, and provided with attaching openings 8 depending upon the type of window frame with which the device is used. Channeled guides 10 are provided which extend vertically along the window frame A, and if it is so desired a cross channeled housing 11 may be provided for enclosing the roller 1. The vertical guides 10 comprise channel plates 12 and the angle plates 13 which are attached to the window frame A in spaced relation to provide the guiding spaces or channels 14 in which the edges of the screen 2 are mounted. The vertical edges of the screen 2 are reinforced by strips 15 of flexible metal, which strips are in turn braced at spaced points by transverse braces 16, the ends of which are angled as shown at 17 for engaging along the edges of the guides 18, as clearly shown in Fig. 6 of the drawings. The guiding strips 18 are carried by the inner sides of the plates 12 and 13.

The outer pointed edges 20 of the channel plates 12 are provided with a plurality of spaced openings 21 which are adapted to receive the latch bolts 22 to releasably hold the screen 2 in adjusted positions. The latch bolts 22 are slidably carried by suitable guide blocks 23 and they are urged into latching position by means of springs 24. A thumb button 25 is carried by each of the bolts 22 and is movable in a slot 26 to permit individual adjustment of the latch bolts on the opposite sides of the screen. To permit unitary movement of the latch bolts, they each have connected thereto, by means of the threaded ends 27 of the stems 28, bars 29 which are in turn eccentrically connected to a disc 30. The disc 30 is rotatably supported by the bracing plates 31 which are attached to the lower edge of the screen 2 and which has a thumb nut 33 carried thereby to facilitate its rotation. The disc 30 is provided with a notch 34 in its perimeter which is adapted to receive the bill 35 of the pawl 36 for locking the bolts 22 in screen unlocking position.

Transversely bent flanges 37 are formed on the lower edges of the plates 31 and they are provided with openings 38 intermediate their ends which are adapted to receive the hook end 39 of a rod 40 to permit the reach,

ing and lowering of the screen when the lower edge is at its uppermost position. A suitable socket 41 is carried by the channel member 12 for normally supporting the rod 40.

If it is so desired the screen 2 may be reinforced by longitudinal and transversely extending strips 43 of flexible metal to prevent buckling of the screen.

From the foregoing description taken in connection with the accompanying drawings it will be apparent that the improved screen may be quickly and easily attached either to the inside or to the outside of a window construction, and that it also may be easily adjusted independently of movement of the window into open or closed or partially opened position being securely held in position by means of the latch bolts 22 which latter may be operated independently by means of the thumb members 25 or in unison through the medium of the disc 30.

It is, of course, to be understood that the invention may be constructed in other manners and the parts associated in different relations and, therefore, I do not desire to be limited in any manner except as set forth in the claim hereunto appended.

Having thus described my invention what I claim is:

In combination, latching means for a window screen including substantially channel shaped guiding members extending along corresponding edge portions of a screen

member and having openings formed therein, a bracing plate adapted to be attached to the lower edge portion of the screen member, guiding blocks having open ends and adapted to be carried by the bracing plate at opposite end portions thereof, latch bolts 40 slidably associated with the guiding blocks, and having end portions adapted for projection through the openings, spring members operable on the latch bolts for urging the end portion of the latch bolts into projecting position through the openings, said guiding blocks having openings in the face thereof, handle portions on said latch bolts protruding through said openings, and adapted for manipulation to move the ends 50 of said latch bolts from projecting position through the openings, and means for connecting the latch bolts for simultaneous operation permitting the end portions to be moved in unison from projecting position through 55 the openings, said means including a disc rotatably supported by the bracing plate and having a notch formed in the rim thereof, rod members having end portions eccentrically connected to the disc and opposite 60 end portions connected to the latch bolts, and a member pivotally connected to the bracing plate and having a bill adapted for engagement with the notch, substantially as described.

In testimony whereof I affix my signature.

PETER SCHNURR.
